UNITED STATES PATENT OFFICE.

HARRY D. ELSE, OF WILKINSBURG, PENNSYLVANIA, ASSIGNOR TO WESTINGHOUSE ELECTRIC & MANUFACTURING COMPANY, A CORPORATION OF PENNSYLVANIA.

THERMOSTATIC CONTROL FOR IRONING MACHINES.

Application filed May 15, 1924. Serial No. 713,437.

My invention relates to thermostatic devices for controlling temperature and it has special relation to temperature control devices applied to ironing machines.

5 One object of my invention is to provide a simple device for longitudinally adjusting a rod, whereby an operator may control the temperature at which an ironing member will be thermostatically maintained.

10 Another object of the invention is to provide a simple device for varying and indicating the temperature at which an ironing member will be thermostatically maintained.

15 A further object of my invention is to provide a connection between a rod and a valve which will permit relative movement of the valve and the rod without impairing the accuracy of the thermostatic control.

20 Reference is had to the accompanying drawing, in which

Figure 1 is a rear elevational view of an ironing machine embodying my invention;

25 Fig. 2 is an enlarged view of the ironing shoe shown in Fig. 1 and of certain elements of my invention, the upper part of the shoe being broken away;

Fig. 3 is a view similar to Fig. 2, parts being shown in section; and

30 Fig. 4 is an elevational view of parts shown in Fig. 2, looking at the left-hand end of the mechanism.

In the illustrated embodiment of the invention, the shoe 1, of any desired construction, has a support 2 secured to one end thereof in which a plug 3 is threaded. The other end of the plug 3 is secured in a tubular rod 4 that extends longitudinally of the shoe 1 to a point adjacent a casing 5 that is secured to the shoe 1 in a manner presently to be described.

40 The casing 5 is provided with a dial 6 with which a pointer 7 co-operates, the pointer being made of sheet metal and fitting about the rod 4 and secured thereto by means of bolts 8.

The dial 6 may be calibrated to indicate temperatures, or otherwise appropriately marked to indicate the ironing condition of the shoe 1. A plug 10 is secured in this end of the rod 4 and has a conically formed recess 11 therein to receive a ball 12. A stem 13 is fitted, at one

50 end, for longitudinal and rotative movement in the recess 11 and engages the ball 12. The stem 13 is also received in, and is capable of sliding and rotative movement in, an elongated guide 14 which is cast integral with the

55 casing 5. The other end of the stem 13 pro-

jects beyond the guide 14 and is slidably fitted in a recess 15 in a valve 16. The innermost part of the recess 15 is conically formed and receives a ball 17 with which the end of stem 13 engages.

60 The valve 16 is enclosed within a cap 18 that is detachably secured to the casing 5 at one end and, at the other end, to a cock 20, which provides a manual control for the admission of fluid fuel from tube 21. A spring 22 is compressed between the cap 18 and the valve 16 to urge the valve toward an annular valve seat 23 on the casing 5. When the valve 16 rests against the valve seat 23, it closes the opening to a chamber 24 in the casing 5 which extends upwardly about the guide 14, but fluid is at all times admissible from the interior of the cap 18 to opening 24 through a by-pass 25.

65 To facilitate manufacture, the casing 5 is cast with the chamber 24 open at the top, and is associated with the shoe 1 by being first secured, by screws 27, to a plate 26 which overlies the open upper end of the chamber 24. The plate 26 is, in turn, secured to the 70 shoe 1 by bolts 28. One end of a pipe 29 is screwed into the wall of the casing 5 to communicate with the chamber 24 and its other end is connected to the burner 30 of the shoe 1, by means of a coupling 31.

75 The shoe 1, when heated, expands with respect to the rod 4, which is preferably of some relatively inexpandable material. The relative expansion of the shoe and rod produces relative movement between the casing 5 and the stem 13. An operator may vary the temperature at which these thermally related or thermostatic elements maintain the shoe 1 by manually moving the pointer 7 relatively to the dial 6, thus causing longitudinal movement of the plug 3 in the support 2, the effect being to substantially vary the operative length of the rod 4.

80 Relative rotary movement, under certain circumstances, occurs between the rod 4 and the stem 13 and, when the valve 16 is brought into contact with the valve seat 23, relative longitudinal movement may occur between the stem 13 and the rod 4. Where sliding movement occurs between the stem 13 and the rod 4 and the stem is again brought into engagement with the ball 12, the effective operating length of the rod 4 upon the valve 16 is unchanged because the ball 12 returns to its original position in the conical por-

100

105

110

tion of the recess 11 and is engaged with the central portion of the flat face of the stem 13.

Though the construction wherein the ball 12 is used is most advantageous, applicant 5 does not limit himself to the details of this construction. If the ball 12 were omitted, and the stem 13 were rounded at its end to have the curvature of a sphere ellipsoid or the like, the resulting arrangement would 10 embody some of the principles of applicant's device and, although the ball construction is preferred, no disclaimer whatsoever of any form is made.

The novel connection between the stem 13 15 and the rod 4 has a further advantage. If the stem 13 were rigid with the rod 4, difficulty would occur in securing the rod 4 to the support 2 and in so aligning it with the bore of the guide 23 as not to cause undesirable friction in the guide 23. The slight 20 looseness of fit, in my construction of the stem 13 in the recess 11, allows for possible misalignment of the rod 14.

From these considerations, the utility of 25 the provision of the ball 17 in the recess 15 is apparent. It permits the valve 16 to fit squarely against the valve seat 23, irrespective of the occurrence of relative rotary movement between the valve 16 and the valve 30 stem 13.

The cap 18 may be detached from the casing 5 to permit cleaning of parts. The spring 22, the valve 16, the valve stem 13 and the balls 17 and 12 may then be removed. This 35 cleaning may, therefore, be accomplished without detachment of the casing 5 or the support 2 from the shoe and without disturbing the setting of the pointer 7 with respect to the dial 6.

40 The guide 14 is strong and, because of its considerable length, tends to prevent lateral movement of the stem 13 and provides a seal that is effective to prevent the escape of the heating fluid.

45 The invention is not limited to the specific details of construction and arrangement of parts described and illustrated which may be extensively modified and varied without departing from the spirit of the invention.

50 I claim as my invention:

1. The combination of an ironing member having an opening therein for the passage of fluid, a valve for restricting said opening, a second member having a connection with 55 said valve, said second member being operative on the movement of the ironing member in one direction to vary the relative position of said valve and said ironing member, said connection permitting rotation of said valve 60 with respect to said second member without varying the relative longitudinal position of said valve and said second member.

65 2. In an ironing machine, the combination of a member having an opening therein for the passage of fluid, a valve for controlling

the passage of fluid through said opening, a spring for urging said valve in one direction, a second member for moving said valve in the other direction, and connecting means between said valve and said second member 70 to permit relative rotary movement between said valve and said second member but preventing lateral movement of said valve with respect to said second member.

3. The combination of an ironing member, 75 a rod secured to one end thereof, an elongated member and connections between said elongated member and said rod, said connections being adapted to permit relative rotary movement of said elongated member and said rod 80 without varying the longitudinal positions of said elongated member and said rod with respect to each other.

4. In an ironing machine, the combination of an ironing member, a rod, an elongated member, means urging said elongated member toward said rod, and means connecting said elongated member to said rod and permitting relative rotary movement between 85 said elongated member and said rod but preventing longitudinal movement of said elongated member with respect to said rod.

5. In an ironing machine, the combination of an ironing member, a second member rigid 90 with said ironing member and having a recess therein, a ball in said recess, a guide and a third member slidably in said guide and engaging said ball in said recess.

6. An ironing machine comprising an ironing member, a rod secured to one end thereof, 100 a second member secured to the other end of said ironing member and having an opening therein for the passage of fluid, a valve for controlling the passage of fluid through said opening and having a recess therein, a ball in said recess, a recess in said rod, a second ball in said recess, and an elongated member engaging said balls.

7. An ironing machine comprising an ironing member, a rod secured to one end thereof, a second member secured to said ironing member and having an opening therein for the passage of fluid, a valve for controlling the passage of fluid through said opening and having a recess therein, a spring for urging said valve in one direction, a ball in said recess, a recess in said rod, a second ball in said recess, and an elongated member engaging 110 said balls.

8. In an ironing machine, the combination of an ironing member, heating means therefor, a pair of members adapted by their relative positions to control said heating means, a rod rigid with said ironing member and adapted to act directly on one of said pair of members for varying the relative positions of said pair of members, said ironing member, said heating means, said pair of members and said rod co-operating to maintain said ironing member at a predetermined temperature, 120 125 130

and means on said rod for indicating said temperature.

9. In an ironing machine, an ironing member, heating means therefor, a valve for controlling said heating means, a rod rigid with said ironing member and adapted to act directly on said valve, means co-operating with said ironing member, said valve and said rod for maintaining said member at a predetermined temperature, and means on said rod for indicating said temperature.

10. An ironing machine comprising an ironing member, a rod secured to one end of said ironing member, a second member having an opening therein for the passage of fluid, a valve for controlling the passage of fluid through said opening, a spring for urg-

ing said valve in one direction, said rod being adapted to move said valve in an opposite direction, and a pointer secured to said rod and adjustable thereon.

11. In an ironing machine, the combination of an ironing member, a rod secured to one end of said member, a second member having an opening therein for the passage of fluid, a valve for controlling the passage of fluid through said opening, a dial on said second member, and a pointer on said rod adapted to co-operate with said dial, said pointer being adjustable rotatively with respect to the rod.

In testimony whereof, I have hereunto subscribed my name this 24th day of April, 1924.

HARRY D. ELSE.
